UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

BOBBIN GUIDE FOR FILLING-REPLENISHING LOOMS.

Application filed October 14, 1926. Serial No. 141,616.

This invention relates to filling replenishing looms of the general type shown in U. S. Patent No. 529,940 and is more particularly directed to means for guiding the filling carrier from the hopper to the shuttle on replenishment of filling.

In the general type of looms to which the present invention relates, there is a bobbin throat extending from the hopper towards the shuttle and through which the filling carrier is passed during replenishment of filling. The front wall of the bobbin throat has ordinarily been constructed as a fixed bobbin abutment against which the head of a filling carrier rests when the filling carrier is moved by the hopper into replenishing position. In some cases the front wall of the bobbin throat has been constructed as a bobbin guide and has been mounted for yielding movement towards the front of the loom, in order to permit the filling carrier to be passed through the throat during replenishment of filling.

It happens at times during weaving that the shuttle entering the replenishing shuttle box will be misplaced to some degree. This is due in many cases to the fact that the shuttle checking or arresting means acts most energetically upon the leading end portion or breast of the shuttle, so that the trailing end of the shuttle as it enters the box is liable to be deflected upwardly at times, and since the front wall of the bobbin throat is opposite the trailing end of the shuttle the latter is liable to strike the front bobbin guiding wall and cause injury to or breakage of parts.

One of the objects of the present invention, therefore, is to provide a front bobbin guiding abutment, forming the front wall of the bobbin throat, which shall be normally held in raised position such that should the shuttle be misplaced in the shuttle box, it will not on beat-up movement of the lay engage the front bobbin guide. Since the filling carrier must be directed accurately from the hopper into the shuttle on replenishment of filling, the present invention contemplates means for downward movement of the front bobbin guiding wall during transfer of a filling carrier from the hopper to the shuttle, the result being that while the front bobbin guiding wall is normally held in a raised position so as not to contact with a misplaced shuttle in the shuttle-box, it is

nevertheless moved downwardly with the filling carrier to bridge the space between the hopper and the shuttle and guide the filling carrier accurately into place, and is returned to its upper or normal position on completion of replenishment.

The invention and novel features thereof will best be made clear from the following description and the accompanying drawings of one good practical form thereof.

In the drawings:

Fig. 1 is a sectional end elevation of a filling replenishing loom provided with the present invention and showing the front guiding abutment in its normal or raised position;

Fig. 2 is a view similar to that of Fig. 1 on a slightly enlarged scale and with parts broken away, showing the relation of parts during replenishment of filling.

Fig. 3 is a perspective view of the trans- 75 ferrer and front bobbin guiding abutment in disassembled relation; and

Fig. 4 is a side elevation showing a modified form of the present invention.

The loom frame 1 may be of usual construction and have mounted thereon the hopper stand 2 on which is supported by the shaft 3 the rotary hopper 4 having the usual heads for the support of the filling carriers 5 which are successively moved to replenishing position by rotary movement of the hopper. The hopper may have rotary movement imparted thereto by any suitable means or be rotated by gravity, as is sometimes the case, but in the present instance 90 of the invention the rotary hopper is provided with the rack teeth 6 which are engaged by suitable means for causing a step-by-step rotation of the hopper on replenishment of filling, but since such means forms no part of the present invention and it is now well understood in the art, a detailed description thereof is unnecessary.

The lay 7 is mounted as usual on the lay swords 8 and is provided with a shuttle box 9 having an open bottom 10 for the passage of the filling carrier in the shuttle during replenishment. These parts may be of usual construction.

Extending from the hopper stand 2 is the support 11 which may be constituted as a dead or stud shaft on which the transffer 12 is mounted. The transffer is provided with a hub portion 13 which surrounds the dead or stud shaft 11 and is normally held

in its raised position by means of a spring 14, and extending downwardly from the hub of the transferrer is the lug 15 on which is pivotally mounted at 16 the dog 17 engageable by a bunter 18 carried by the lay, on call for replenishment of filling. These parts also may be of usual construction.

Leading from the filling carrier hopper is the bobbin throat 19 which in the present instance of the invention has a finger 20 pivotally mounted at 21 and normally held yieldingly in the position indicated in Fig. 1, as usual in this general type of loom.

During weaving, the shuttle entering the filling replenishing box is liable to be misplaced owing to the action of the shuttle checking means, and this is particularly observable at the trailing end portion of the shuttle which is nearer the cloth selvage and substantially opposite the front wall of the bobbin guiding throat. Should the misplaced shuttle strike the front wall of the bobbin guiding throat on beat-up movement of the lay, much damage is liable to occur and breakage of some of the parts. In accordance with the present invention, therefore, the bobbin guiding abutment which constitutes the front wall of the bobbin throat is normally held in a position sufficiently raised that it will not engage a misplaced shuttle in the shuttle box, and is mounted for downward movement with the filling carrier during transfer to accurately guide the incoming filling carrier into proper position in the shuttle.

In accordance with one form of the present invention, the front bobbin guiding abutment 22 extends upwardly into the path of movement of the filling carriers 5 in the rotary hopper, and against the rear face of the front guiding abutment the head of the filling carrier next to be transferred will rest.

As shown, the front bobbin guiding abutment 22 is secured to an arm 23 by appropriate means, such as the pins or rivets 24, and is provided with a hub portion 25 mounted upon the dead or stud shaft 11 or upon the extended sleeve or hub portion of the transferrer 12, the construction being such that the arm 23 and its connected front bobbin guiding abutment may have capacity for upward and downward movement to permit the front bobbin guiding abutment to move downward with the filling carrier during transfer to thereby bridge the space between the hopper and shuttle and guide the filling carrier into the shuttle during the operation of the transferrer.

The front bobbin guiding abutment is normally held in its raised position out of contact with the misplaced shuttle in the shuttle box, and as one appropriate means to this end the arm 23 is under the influence of a spring 26, one end of which is secured to a lug 27 extending from the arm 23, and

the other or free end of which rests upon a fixed support 28, the result being that the spring 26 acts normally to hold the front bobbin guiding abutment in its raised position with its bobbin guiding face in the path of filling carriers in the hopper as the latter is rotated to bring the filling carrier into transferring position.

In accordance with one form of the present invention, the front bobbin guiding abutment 22 is caused to partake of its downward movement with a filling carrier during transfer by means associated with the transferrer. As one good practical form of such means, the transferrer hub is provided with a plunger or yielding abutment 29 which, as shown, may be constituted by a pin 30 passed through the lug 31 carried by the hub portion of the transferrer, and interposed between the plunger head 29 and the bottom of the socketed lug is a spring 31* normally tending to move the plunger upwardly, and limited in the performance of this function by means of a stop 32 which may be constituted as a nut secured to the lower end of the plunger below the socketed portion 31.

The hub portion 25 of the front bobbin guiding abutment carrying arm 23 is provided with a lug 33 shown as extending laterally and into the path of movement of the yielding plunger 29 as the transferrer is given its transferring movement, the result being that the front bobbin guiding abutment 22 will be given a downward movement as the transferrer operates to transfer a filling carrier from the hopper to the shuttle to thereby cause the front bobbin guiding abutment to bridge the space between the hopper and the shuttle and guide the filling carrier accurately into place as it is transferred, and upon upward movement of the transferrer after completion of the transfer the spring 26 will act upon the arm 23 to raise the front bobbin guiding abutment into its initial position with its guiding face in the path of movement of filling carriers as they are moved by the rotary hopper.

In order to limit the upward movement of the front bobbin guiding abutment as it is returned to its normal position, a stop is provided which, in the present instance of the invention, comprises a shoulder or lug 34 extending from the hub portion 25 of the arm 23, and a fixed member 35 which may be appropriately attached to or connected with the hopper stand 2.

The sudden and impulsive movement of the transferrer to effect the transfer of a filling carrier from the hopper through the bobbin throat to the shuttle may cause the lower portion of the front bobbin guiding abutment to engage with the top of the shuttle, and in order to prevent injury to any of the parts in such case the plunger 29 yields when the front bobbin guiding abut-

ment has been arrested in its downward movement by engagement with the top of the shuttle or shuttle box.

Various changes may be made in the details of the present invention, and one of such modifications is indicated in Fig. 4 wherein the front bobbin guiding abutment is carried by an arm 23 as before, and is provided with a lug 36 extending laterally therefrom, and having an inclined face 37, thereby constituting a cam. In this construction, the transferrer downwardly extending arm 15 has pivotally connected to it at 38 the cam member 39 provided with an inclined or cam face 40, and the lower end of the cam member 39 rests upon a fixed support 41, the construction being such that when the transferrer performs its transferring function, the cam 39 is withdrawn 20 frontwardly out of engagement with the lug 36, thereby permitting the arm 23 and its connected front bobbin guiding abutment 22 to drop as the filling carrier is transferred from the hopper through the throat to the 25 shuttle, and when the transferrer is returned to its initial or upper position under the action of the spring 14, the inclined faces 37 and 40 of the lug and cam 39 will act to raise the arm 23 and the front bobbin guiding abutment 22 into their upper position, to thereby place the front bobbin guiding abutment in the path of filling carriers as they are moved by the rotary hopper into position for transfer.

35 In order to prevent overthrow upwardly of the front bobbin guiding abutment in the construction described, the arm 23 may be provided with a stop 42 adapted to engage with a fixed stop 43 secured to the hopper stand or formed as part thereof.

From the construction described it will be apparent that while the present invention provides that the front bobbin guiding abutment shall be normally held in such raised position that it will not be engaged by a misplaced shuttle in the shuttle box on beat-up movement of the lay, the guiding abutment itself will be moved downwardly with the filling carrier as it is transferred to guide the filling carrier accurately into place, and upon completion of replenishment of filling the front bobbin guiding abutment will be raised to its former normal position, thus insuring at all times the accurate guidance of the filling carrier through the bobbin throat into the shuttle, notwithstanding that the bobbin guiding abutment is normally held in raised position out of contacting relation with the misplaced shuttle during beat up movement of the lay.

Should the trailing end of the shuttle be misplaced upwardly in the shuttle box on replenishment of filling, the downward movement of the arm 23 and the front bobbin guiding abutment may engage the

top of the shuttle, with the result that the trailing end of the shuttle will be replaced in proper position in the shuttle box for the next picking movement of the loom.

What is claimed is:

1. In a filling replenishing loom, the combination of a rotary hopper for filling carriers, a transferrer for transferring a filling carrier from the hopper to the shuttle, a front bobbin guiding abutment against which the head of a filling carrier in the hopper rests when moved into transferring position, means normally acting to maintain the bobbin guiding abutment raised in the path of the filling carriers in the rotary hopper to arrest rotary movement of the hopper with the leading filling carrier in the hopper in transferring position and movable on replenishment of filling to permit downward movement of the bobbin guiding abutment from its normal raised position to guide the filling carrier into the shuttle.

2. In a filling replenishing loom, the combination of a rotary hopper for filling carriers, a transferrer for transferring a filling carrier from the hopper to the shuttle, a front bobbin guiding abutment having an upwardly extending face against which the head of a filling carrier rests when in transferring position, a lifter normally acting to hold the bobbin guiding abutment in raised position with its upwardly extending face in the path of the filling carriers in the rotary hopper and movable by the transferrer to permit the bobbin guiding abutment to move downwardly with a filling carrier as it is being transferred to guide the filling carrier into the shuttle.

3. In a filling replenishing loom, the combination of a rotary hopper for filling carriers, a transferrer for transferring a filling carrier from the hopper to the shuttle, a front bobbin guiding abutment engaged by the head of a filling carrier when in transferring position, means normally acting to hold the bobbin guiding abutment in raised position out of the path of a misplaced shuttle in the shuttle box on beat-up movement of the lay and movable by the transferrer to permit the bobbin guiding abutment to move downwardly on transfer to bridge the space between the hopper and shuttle and guide the head of the filling carrier into proper position in the shuttle.

4. In a filling replenishing loom, the combination of a rotary hopper for filling carriers, a transferrer, a front bobbin guiding abutment having an upwardly extending face engaged by the head of a filling carrier in the hopper when in transferring position and mounted for downward movement with a filling carrier during transfer to bridge the space between the hopper and shuttle and guide the filling carrier into the shuttle, and means for again lifting the

bobbin guiding abutment into the path of movement of the filling carriers in the rotary hopper.

5. In a filling replenishing loom, the combination of a horizontal rotary hopper for filling carriers, a transerrer, a front bobbin guiding abutment having an upwardly extending face against which the head of a filling carrier is engaged when moved by the 10 hopper into transferring position, means for normally holding the front bobbin guiding abutment in raised position that it may not be struck by a misplaced shuttle in the shuttle box as the lay beats up and movable on 15 downward movement of the transerrer to permit the front bobbin guiding abutment to move downwardly with a filling carrier during transfer to bridge the space between the hopper and shuttle and guide the filling 20 carrier into the shuttle.

6. In a filling replenishing loom, the combination of a rotary hopper for filling carriers, a transerrer, a front bobbin guiding abutment having an upwardly extending 25 face against which the head of a filling carrier is engaged when moved by the hopper into transferring position, means for normally holding the front bobbin guiding abutment in raised position that it may not be struck by a misplaced shuttle in the shuttle 30 box as the lay beats up, and means actuated by the transerrer for moving the front bobbin guiding abutment downwardly with the filling carrier during transfer to bridge the space between the hopper and shuttle and guide the filling carrier into 35 the shuttle.

7. In a filling replenishing loom, the combination of a rotary hopper for filling carriers, a transerrer, a guiding abutment normally in the path of a filling carrier as the 40 hopper is rotated to place the filling carrier in transferring position, an arm having a vertical movement on which the guiding 45 abutment is mounted and means actuated by the transerrer for moving the arm and guiding abutment downwardly with the filling carrier during transfer for guiding the filling carrier into the shuttle.

50 8. In a filling replenishing loom, the combination of a rotary hopper for filling carriers, a transerrer stud, a transerrer mounted on the stud for transfer movement, a guiding abutment normally in the path of 55 movement of a filling carrier as the hopper is rotated, an arm mounted on the transerrer stud and carrying said guiding abutment, means normally acting to hold the guiding abutment in the path of a filling 60 carrier in the hopper, and yielding means actuated by the transerrer for moving the guiding abutment towards the shuttle during transfer for guiding the filling carrier to the shuttle.

65 9. In a filling replenishing loom, the com-

bination of a hopper for filling carriers, a bobbin throat between the hopper and shuttle for the passage of a filling carrier, the front wall of the throat being formed by a bobbin guiding abutment against which the 70 head of a bobbin rests when the bobbin is in transferring position, the said bobbin guiding abutment being mounted for downward movement while in contact with the head of the filling carrier to bridge the space between the hopper and shuttle during transfer to guide the filling carrier into the shuttle, and means normally acting to hold the front wall of the bobbin throat in a raised 75 position out of the path of a misplaced shuttle in the shuttle box.

10. In a filling replenishing loom, the combination of a hopper for filling carriers, a transerrer, a front bobbin guiding abutment mounted for movement with a filling 80 carrier during transfer between the hopper and shuttle, means normally acting to maintain the front bobbin guiding abutment in raised position out of the path of a misplaced shuttle in the shuttle box, and means 85 actuated by the transerrer on replenishment of filling for causing movement of the front bobbin guiding abutment towards the shuttle to bridge the space between the hopper and shuttle and guide the filling carrier 90 into the shuttle during transfer.

11. In a filling replenishing loom, the combination of a hopper for filling carriers, a transerrer, a front bobbin guiding abutment mounted for movement with a filling 100 carrier during transfer between the hopper and shuttle, means normally acting to maintain the front bobbin guiding abutment in raised position out of the path of a misplaced shuttle in the shuttle box, a stop for 105 limiting the upward movement of the bobbin guiding abutment, and means actuated by the transerrer on replenishment of filling for moving the front bobbin guiding abutment 110 towards the shuttle to bridge the space between the hopper and shuttle and guide the filling carrier into the shuttle during transfer.

12. In a filling replenishing loom, the combination of a hopper for filling carriers, a transerrer, a front bobbin guiding abutment mounted for movement with a filling 115 carrier during transfer between the hopper and shuttle, means normally acting to maintain the front bobbin guiding abutment in raised position out of the path of a misplaced shuttle in the shuttle box, and yielding 120 means actuated by the transerrer on replenishment of filling for moving the front bobbin guiding abutment towards the shuttle to bridge the space between the hopper 125 and shuttle and guide the filling carrier into the shuttle during transfer.

In testimony whereof, I have signed my name to this specification.

HARRY A. DAVIS,
